UNITED STATES PATENT OFFICE.

HOWARD A. CARSON, OF BOSTON, MASSACHUSETTS.

MEANS FOR EXCAVATING DIRT, &c.

SPECIFICATION forming part of Letters Patent No. 268,181, dated November 28, 1882.

Application filed April 10, 1882. (No model.)

To all whom it may concern:

Be it known that I, HOWARD ADAMS CARSON, of Boston, in the county of Suffolk, of the State of Massachusetts, have invented a new and useful improvement in means or mechanism for excavating earth and transporting to and depositing it at a distance from the place of excavation; and I do hereby declare the same to be described in the following specification and represented in the accompanying drawings, of which—

Figure 1 is an isometrical perspective view of an apparatus embracing my invention. Fig. 2 is a similar view of one of its scoops. Fig. 3 is a side elevation, and Fig. 4 an edge view, of the scoop-transporting mechanism, to be described.

The object of my invention is to dispense in a large degree with manual labor, as usually employed in various other earth hoisting and carrying devices heretofore used and provided with tubs to receive and dump the earth, as, in the place of tubs to be filled with the excavated earth by men with shovels, I employ two or more excavating-scoops of peculiar construction, and with such means of supporting them and moving them alternately from the place of excavation to that of deposit of the earth. These scoops are shown in Fig. 1 at H and I, each consisting of a box, a, open in front and at top, as shown in Fig. 2, and provided on the front edge of its bottom with a suitable number of teeth, b, formed as shown, and inclined downward somewhat relatively to said bottom. Besides a main bail, d, arranged with it as represented, it has an auxiliary bail, c, and a supporting-hook, e, therefore, such hook, at the upper part of its shank, being properly hinged to the main bail. The lower part of the hook is bent to an acute angle with the shank, such acute angle approximating closely to a rightangle. Besides the above-mentioned appliances, there is to the scoop a drag-bail, f, to extend from it in manner as shown in Fig. 2. To this latter bail power is to be applied in any suitable manner, to draw forward the scoop to cause it to enter and scoop up the earth. Each scoop has its main bail hitched upon a hook, g, depending from a pulley, h. (See Figs. 3 and 4.) This pulley is hinged to an eyebolt, i, provided with a heavy washer, k, arranged on it

in manner as shown, such washer being to prevent the block from being raised too high. The bolt i extends downward from a conic frustum, shown in dotted lines in Fig. 3, at l, as resting on two movable jaws, m m, arranged in a traveler, A, in manner as represented, and having studs m' projecting from them into slots n formed in a flat lever, B, fulcrumed to the traveler at O, and resting when horizontal upon a projection, p, extending from the traveler. A rope, q, fastened to the lever serves to enable a person to turn it on its fulcrum in a manner to simultaneously force upward the said movable jaws in order to allow the scoop to descend. The frustum l is attached to a rope, r, led through the pulley and about two grooved wheels, s s, arranged in the traveler in manner as represented. The said traveler, 70 constructed as shown, is suspended from a carriage or bicycle, C, adapted to run upon a sustaining-rope, D, the traveler being connected to such carriage so as to be capable of swinging laterally below it in a manner to 75 maintain its verticality while the carriage is being moved along its supporting-rope D.

The travelers A of the two scoops are shown in Figure 1 as connected by what I term a "tail-rope," E, which goes through leading-pulleys t t at the upper part of a supporting standard or frame, F, the rope at one or each of its ends being fastened to and wound upon a drum, u. One or each traveler has such a drum, u, journaled to and arranged with it, as shown in Figs. 3 and 4. The heads u' of the drum, formed with stop-shoulders v, serve with a slide, w, arranged in the traveler to retain the drum from revolving under the strain of the rope after such rope may have been wound on the drum. The slide w is a block of wood or piece of metal adapted to the traveler A, so as to be capable of being slid or moved toward and away from the heads u' u' of the drum u, such being in order that when the slide 95 may be against the said heads and their two opposite stop-shoulders may be resting on the slide, they, with the slide, shall prevent the drum from revolving under the strain of its rope.

The sustaining-ropes D D of the two carriages or bicycles extend between and are supported by two wooden frames, F G, constructed and arranged as shown in Fig. 1, and suitably

ballasted, as at $w' w'$, each of the said ropes being fastened to one of two crabs, x , sustained by the frame G. Each crab consists of one axle or barrel, with means of revolving it to wind the rope upon it, the barrel also being provided with a ratchet-wheel and pawl to hold it from revolving backward after the rope may have been wound sufficiently on it. The frames F G are provided with runners y to rest on rollers z , that in turn rest on planks a' , arranged as shown, such being to enable the frames to be moved laterally as occasion may require. The tendency of the two frames to be drawn toward each other may be counteracted by oblique struts b' , extending from them into the ground and against stones or timbers thereon.

Within the frame G, I usually arrange the motor for effecting the reciprocation of the scoop-travelers. This motor is shown at I', which may be a steam-engine applied to an upright boiler. In front of the motor are two drums, K L, to which are fastened the two ropes r of the two travelers. The drums are to be suitably connected with the steam-engine to enable them to be revolved, as occasion may require, to cause either rope r to be wound upon its drum and the other rope to be simultaneously and in like manner unwound from its drum, or to be kept from unwinding.

From the above it will be seen that by means of the ropes r and the tail-rope connecting the two travelers they may be caused to simultaneously move in opposite directions along and below the supporting-rope of their carriages or bicycles, and either of the scoops may be lowered to a position for excavating and the other be raised to a position for discharging earth, the excavating of the earth being caused by drawing the scoop laterally by its drag-bail so as to cause it to enter and scoop up the earth until it may be sufficiently laden therewith. On each scoop being carried over the place upon which its load is to be discharged, an attendant should strike upon the hook connecting the main and auxiliary bails with force sufficient to disconnect the hook from the auxiliary bail, which having taken place, the scoop will by the weight of its load be turned downward so as to discharge or dump such load.

I would remark that in several respects the earth excavating and transporting mechanism herein described is analogous to the apparatus heretofore patented by me for hoisting and moving earth in trenches; but it differs therefrom in several important particulars, as my present apparatus is an earth excavator and transfferer, which the patented one was not, and, besides, has movable and ballasted frames and sustaining-ropes for the scoops and their travelers, and such travelers are supported

from separate carriages or bicycles, so as to maintain their vertical positions under any curvature or sag of the sustaining-ropes without tipping the carriage so as to cause them to bind with injurious friction on the ropes.

It is to be further remarked that the same engine which hoists, lowers, and moves horizontally the scoops heretofore described may also, though not necessarily, furnish power for dragging and filling the scoops. In this case a third winding-drum, or a so-called "gypsy-head," (not shown,) may conveniently be employed.

With the rope and bicycle thereon and the traveler connected with the bicycle as described, the traveler can be moved under and laterally of the rope, and also in the plane of the rope, which cannot be done when the traveler is of itself a carriage supported on a rigid rail or track.

Having thus described my improved earth excavating, transporting, and discharging apparatus, which in practice has been found to be highly advantageous and economical, what I claim as of my invention is as follows, viz:

1. The open-box scoop having the inclined teeth b , and provided with the three bails, f , c , and d and the hook e , arranged and adapted substantially as set forth. 90

2. The traveler A , provided with the block h , rope r , wheels $s s$, drum u , and rope E , and suspended from the bicycle between its wheels, and jointed to it so as to be capable of being swung laterally under the bicycle and in the plane thereof. 95

3. The combination of the rope D , the bicycle C , and the traveler A , provided with the block h , rope r , wheels $s s$, drum u , and rope E , and jointed to the bicycle and arranged with it and the rope, substantially as set forth. 100

4. The combination of the pawl or slides w and the tail-rope drum u , having one or each of its heads provided with stop-shoulders v , as described, with the scoop-travelers, and also with the tail-rope adapted to such drum, as set forth. 105

5. The combination of the movable and ballasted frames F G, as described, and their traveler-bicycle supporting-ropes D , extending from one to the other of such frames, with the two travelers A , their bicycles C , scoops H and I , tail-rope E , and scoop lowering and raising ropes r , all being arranged and applied essentially in manner and to operate as set forth. 110 115

HOWARD ADAMS CARSON.
